UNITED STATES PATENT OFFICE

HERMAN SCHULTZ, OF PARKERSBURG, IOWA, ASSIGNOR OF ONE-EIGHTH TO R. J. GOERNER, OF PARKERSBURG, IOWA.

DETACHABLE HANDLE FOR JARS.

1,220,466.

Specification of Letters Patent. Patented Mar. 27, 1917.

Application filed February 26, 1914, Serial No. 321,262. Renewed August 14, 1916. Serial No. 114,889.

To all whom it may concern:

Be it known that I, HERMAN SCHULTZ, a citizen of the United States, residing at Parkersburg, in the county of Butler and State of Iowa, have invented certain new and useful Improvements in Detachable Handles for Jars, of which the following is a specification, reference being had to the accompanying drawings.

10 This invention relates to new and useful improvements in detachable handles for receptacles, such as jars and the like.

The object of this invention resides in the provision of a handle means which may be very readily and quickly attached to a receptacle such as a jar or the like so that it may be conveniently carried about from place to place, said handle means being of such construction that it may be readily detached from the receptacle.

15 It is further the object of the present invention to provide such a handle means which possesses a full degree of adjustment so that it is readily applicable to receptacles of widely varying sizes.

20 It is still further the object of this invention to provide a handle means of the nature described which is of such simple construction that it may be very cheaply manufactured, this advantage being procured without departing in any manner from the advantages set forth.

With the above and other objects in view, the invention resides more fully in the novel combination, formation and arrangement of parts more fully hereinafter described and particularly pointed out in the claim hereto appended.

25 Reference is had to the accompanying drawings in which similar characters of reference designate corresponding parts throughout the several views and wherein,

Figure 1 is a side elevation of the upper portion of a jar, with the improved detachable handle means attached thereto.

Fig. 2 is a top plan view of the detachable handle means.

Fig. 3 is a perspective view of the locking member of the device.

30 Fig. 4 is a plan view of one of the members for adjusting the diameter of the jar engaging portion of the device.

Fig. 5 is a vertical sectional view taken centrally through said adjusting means.

Fig. 6 is a detail side elevation of the said 35 adjusting means; and

Fig. 7 is an end view of the said adjusting means.

Referring more particularly to the accompanying drawings, there are provided a pair of hand grips 5 and means for tightly securing these hand grips to any desired size of receptacle, such as a jar or the like.

This means for securing the hand grips comprises a pair of wire sections 6 which 65 have adjacent ends adjustably connected together as will be explained. The other end portions of the sections have their extremities bent backwardly and coiled around the sections, as at 7 to form the loops 8. A locking lever is provided which comprises a plate 9 provided adjacent the outer side of one end portion with an opening 10 through which is passed one of the loops 8. The inner face of the plate 9 is provided with a 75 plurality of teeth 11 which extend outwardly at an acute angle. The other loop 8 is adapted to be engaged between two of these teeth and the lever then swung to tightly bind the wire sections around the receptacle. It is observed that as the plate 9 is swung against the receptacle, the pivotal connection formed by the loop 8 at the opening 10 will be moved outwardly of the pivotal connection of the other loop 8 so that 80

the tension exerted by the wire will serve to hold the locking plate 9 in locking position. By providing a plurality of teeth, it is seen that considerable adjustment may be had. The hand grips are positioned on the 85 U-shaped lengths 12 of wire, which have the extremities of their arms formed with eyes 13 embracing the section 6.

It is thus seen how two adjacent ends of the sections are manipulated to bind the sections around the receptacle. To adjustably connect the other ends of the sections, pairs 95 of plates 14 are provided. The plates of each pair have their opposed faces formed with opposed grooves 15 and the wire sections are passed through these grooves. A clamping screw 16 is passed through each pair of plates and thus clamps the wire sections against movement relative to the plates 14. Each end of one of the wire sections is 100 firmly secured to an outer plate 14. To accomplish this, the plate is provided with an opening 17 extending from the one end por-

tion of a groove 15 to the outer face of the plate, and the extremity of the wire section is extended through the groove and around the edge of the plate, and then into the opening 17, as shown at 18.

From the foregoing it will be seen that an exceedingly simple and efficient handle means has been provided which may be very readily attached to or detached from a receptacle and which may be constructed so as to be easily adjustable for various sizes of receptacles.

Having thus described this invention, what is claimed is:—

15. A detachable handle member comprising a pair of wire sections, pairs of plates provided with opposed longitudinal grooves co-acting to receive the sections, clamping

screws passed through each pair of plates, one of the plates of each pair being provided with an opening extending from one of the grooves outwardly, and the wire adjacent said opening being extended therethrough and directed around the edge of the plates handles carried by the sections, and means associated with the other ends of the sections for drawing them together into clamping relation and holding them in such position.

In testimony whereof I hereunto affix my signature in the presence of two witnesses.

HERMAN SCHULTZ.
